UNITED STATES PATENT OFFICE

108,595

DESIGN FOR A COMBINED BOOK AND NEWS- PAPER HOLDER

James I. Kumauchi, New York, N. Y.

Application November 11, 1937, Serial No. 72,813

Term of patent 14 years

To all whom it may concern:

Be it known that I, James I. Kumauchi, a citizen of Japan, residing at New York city, in the county of New York and State of New York, have invented a new, original, and ornamental Design for a Combined Book and Newspaper Holder, of which the following is a specification, reference being had to the accompanying drawing, forming part thereof.

The figure is a perspective view of a combined book and newspaper holder, showing my new design.

I claim:

The ornamental design for a combined book and newspaper holder, as shown.

JAMES I. KUMAUCHI.
